(57) **CLAIM**

The ornamental design for a secure password organizer, as shown and described.

DESCRIPTION

FIG. 1 is an upper end view of the password organizer, the opposing side being a mirror image;

FIG. 2 is a top plan view of the password organizer of FIG. 1; FIG. 3 is a side view of the secure password organizer of FIG. 1, the opposing side being a mirror image; and,

FIG. 4 is a bottom plan view of the secure password organizer of FIG. 1.

The superimposed broken line showing of the text and other graphical indicia in FIG. 2 and the superimposed broken lines in FIG. 4 form no part of the claimed design.
